ANDRÉ VARAUD, OF GENEVA, SWITZERLAND.

PERCUSSION FUSE FOR PROJECTILES.

Application filed May 16, 1928, Serial No. 278,104, and in Switzerland July 19, 1927.

This invention concerns improvements in percussion fuses for projectiles of the kind having a relatively movable percussion pin and primer-carrying member, functioning under the action of inertia, mounted so as to be axially movable within the fuse and normally held apart by centrifugal means, themselves normally locked in operative position by inertia-operated members.

Such fuses have been provided with various means, either an antagonistic spring or a pin perpendicularly traversing the percussion pin and the body of the fuse, to prevent untimely action of the percussion pin on the primer due to the resistance of the air acting on the point of the projectile during its trajectory. It is true that there is thus obtained a certain safety of action, but this only at the expense of the sensitiveness of the fuse since at the impact the percussion pin has to overcome the resistance of said safety-means.

Apart from this disadvantage, in fuses of this type the point of the striker is always held at a certain distance from the primer (up to 3 to 4 millimetres) which removes a large part of the instantaneous action on impact if the obstacle encountered by the point of the projectile is of weak consistency.

The percussion device (movable slide and striker), even when lightened as much as possible or made of material of a low density such as aluminium or electrum, weighs several grammes and thus possesses large momentum and energy. For a given force, the reaction rearwardly towards the primer is very small if the obstacle encountered is of feeble consistency.

In this case, the stoppage of the striker not being sufficiently rapid, the time taken to traverse the space separating it from the primer reduces the effect of the burst, since the projectile only bursts when it has already buried itself for some distance. The instantaneous bursting action desired is thus not obtained, from which results the inefficacy of this kind of device.

It would appear that, to solve these problems and provide sensitive or instantaneous action fuses, there could be provided a construction in which the spring between the primer and striker is weakened as much as possible, even below the force necessary to counterbalance the pressure of the air on the

striker pin, means being provided to permit progressive movement of the striker towards the primer during the trajectory only after the projectile has traversed a certain part of its trajectory. It is, however, known that at the discharge the projectile is subjected to violent oscillations which may cause premature bursting if the fuse is made as sensitive as possible in the manner described.

It will be seen, on the other hand, that when the projectile has reached "steady" flight after a certain part of the trajectory is completed, the risk of premature bursting may be obviated even with a sensitive fuse if the progressive movement of the striker towards the primer is caused solely at this time.

The object of the present invention is to provide a fuse of the kind in question having great sensitiveness but also being safe in use. For this purpose there is provided a centrifugal member having rack teeth held engaged until the moment of firing between the striker and primer, in such manner as to prevent untimely movement thereof but to permit during the trajectory progressive movement of the striker towards the primer. The toothed centrifugal member meshes to that and with a wheel train of which the last movable wheel is braked by an escapement member disposed eccentrically of the axis of rotation of the projectile so as to be subjected to the action of centrifugal force, the braking of the wheel being thus proportional to the speed of rotation of the projectile and the whole arrangement being such that contact may be established between the striker point and the wall of the primer after a predetermined time.

The annexed drawings show, by way of example, two forms of construction of the device according to the invention.

Fig. 1 is an axial section of the first form of construction in the position for transport, a tight hood and protective sleeve being provided.

Fig. 2 is a transverse section on the line A—A Fig. 1.

Fig. 3 is an axial section of this construction in the position for transport showing the train of wheels.

Fig. 4 is a plan of the body of the fuse, the head being removed to show the arrangement within this body.

Fig. 5 is an axial section of the same con-

struction showing the position of the parts on the departure of the shell during the acceleration, the hood and protector being removed.

Fig. 6 is also an axial section, showing the 5 fuse on impact.

Fig. 7 is an axial section of the second construction in position for transport and having a protective sleeve.

Figs. 8 to 10 are axial sections similar to 10 Fig. 7 showing the fuse on the departure of the shell, during the trajectory and on the moment of contact of the striker on the primer at impact.

Fig. 11 is a transverse section on the line 15 A—A of Fig. 7.

Fig. 12 is a plan of the body of the fuse, the head being removed to show the parts detachably mounted in this body.

Fig. 13 is a detail sectional view on the 20 axes of the clockwork wheels.

Figs. 14 to 16 are respectively an axial section, a partial elevation and a plan of a modification, the head being removed.

Referring to Figs. 1 to 12, it will be seen 25 that the striker 1 is mounted so as to be axially movable in the percussion-control guide 2, which is itself axially movable in the head 3 of the fuse.

This mounting of the striker is adopted to 30 prevent the impulse received, when shocks are produced during handling of the shell either directly or indirectly by inertia, from being transmitted to the striker from the guide 2. To that end a damping spring 4 is 35 housed in the front of the guide 2 so as to bear on a shoulder 5 on the striker and on a plug 6 screwed into the end of the guide. This spring is of a size and diameter such as to offer a sufficiently large resistance (about 14 40 to 15 kgs) to compression so as to absorb shocks on the point of the guide 2 either during handling or by inertia on the departure of the shell if, for example, firing is effected in a wood and the point strikes the branch of a 45 tree.

The striker 1 and the inertia plug 26 are held spaced from the primer 7 during transport and on the departure of the projectile by a radial bolt 8 having rack teeth referred 50 to hereinafter. This bolt has a central longitudinal slot 9 traversed perpendicularly by the point 10 of the striker 1, which normally rests by its shoulder on the bolt 8 as shown in Figs. 1 and 7.

55 The forked extremity of the bolt is bevelled at 11 so as to allow the striker to move progressively and gradually towards the primer when the bolt is retracted under the action of centrifugal force. The bolt 8 is maintained 60 in the operative position during transport by an inertia pin 12 (Fig. 11) of known form having claws or a spring and provided with a portion engageable in a corresponding transverse hole in the bolt.

65 As the inertia pin 12 might be retracted at

small accelerations it is necessary to provide means for holding said pin for safety in transport so that it is kept in operative position until the moment of firing, such as by means of a pin 19' engaged in an axial hole in the 70 bolt 8 and fixed by means of a plug 22 (Figs. 7 to 16).

The rack teeth cut on the bolt 8 control a train of wheels 13 housed in the body 14 of the fuse by means of a pinion 15 (Figs. 1 to 4 75 and 11 to 13). The last movable member of the train 13 is an escapement wheel 16 which co-operates with an anchor 17 oscillable about a pivotal axis eccentric with respect to the axis of the projectile (Figs. 4 and 12). 80 This anchor is slightly out of equilibrium (Fig. 12) so that one of its arms is pushed under the action of centrifugal force, on the teeth of the escapement wheel 16 in such manner that the braking of this latter is proportional to the centrifugal force, in accordance with the speed of rotation of the projectile. The important part played by this anchor placed out of equilibrium by its eccentric 85 mounting will thus be evident.

90 Experiments have shown that, due to this peculiarity of the anchor, the interval between firing and the moment at which the striker contacts with the primer is substantially the same in these fuses notwithstanding variations of initial speeds between 250 and 500 metres and of rotational speeds between 6,500 and 15,000 revolutions per minute, thus proving the efficacy of the braking which is in fact proportional to the speed of rotation of the 95 projectile.

The housing enclosing the train of wheels 13 and the escapement arrangement 16, 17 is in two parts 23, 24 detachably mounted in the body 14 (Figs. 12 and 13).

100 The functioning of this fuse is as follows: At the moment of firing, the members 18, 19 in the first form (Figs. 1 to 6) and in the second form (Figs. 7 to 16) the pin 19' is first removed, the fuse being then ready for use. On the departure of the shell (Figs. 5 and 8) the guide 2 descends under the action of inertia on to the plate 20, screwed in the head 3, compressing the spring 4. When the linear acceleration ceases, the guide 2 reascends under the action of the spring 4 into the position shown in Figs. 1 and 7 whilst the bolt 8, under the effect of centrifugal force, commences to drive the pinion 15 and the train 13 while maintaining the striker 1 115 out of reach of the primer.

120 The escapement device 16, 17 then acts as a brake to slow down the radial displacement of the bolt 8 to allow the shell to travel a sufficient distance prior to the striker coming into contact with the primer or detonator.

When the slope 11 of the bolt 8 arrives against the shoulder of the striker 1 the latter, due to the air resistance acting on the guide 2, moves gradually towards the primer 130

7 until it finally rests thereon, as in Fig. 9. The fuse is then ready to function at the occurrence of the slightest impact.

5 A weak spring 21 is interposed between the slide 2 and the lower part 14 of the body or the plate 23 so as partially to counterbalance the action of the air on the slide 2, thus obviating any risk of the primer being perforated due to the air pressure.

10 Due to this contact of the striker point on the primer, there is obtained a very sensitive action but the use of the spring 21 prevents any premature action of the primer, it being understood that a relatively large force 15 is required to cause perforation thereof. The primer-carrying plug 26 operates by inertia in well-known manner.

It may be advisable in some cases with a view to ensuring bursting when the angle 20 of the shell-trajectory is small or on slopes (which, as is known, are liable to cause misfire) for the fuses not to embody such inertia-operated means.

25 Figs. 14 to 16 show a modification in which the spring 4 and inertia plug 26 are omitted and in which the pin 19, instead of having a loop for removal, is provided with a tongue 25 fitting in or welded (soldered) into a corresponding groove in the body 14 having 30 a loop for pulling off at the moment of firing.

What I claim is:

1. A percussion fuse for projectiles comprising in combination a striker, a primer, a housing in which said striker and primer are mounted so as to be movable relatively one to the other, a radial bolt-member normally separating said striker and primer but being slidably mounted in said housing to allow contact thereof during the flight of the projectile, an escapement device driven from and braking the movement of said bolt, said escapement being eccentrically positioned with regard to the fuse axis, and means for preventing movement of said bolt until the departure of the projectile.

2. A percussion fuse for projectiles comprising in combination a striker, a primer, a housing in which said striker and primer are mounted so as to be movable relatively one to the other, a guide in said housing for said striker, a first spring being interposed between said striker and guide, a second spring between the housing and the guide, a radial bolt-member normally separating said striker and primer but being slidably mounted in said housing to allow contact thereof during the flight of the projectile, an escapement device driven from and braking the movement of said bolt, said escapement being eccentrically positioned with regard to the fuse axis, and means for preventing movement of said bolt until the departure of the projectile.

3. A percussion fuse for projectiles com-

prising in combination a striker, a primer, a housing in which said striker and primer are mounted so as to be movable relatively one to the other, a radial bolt-member normally separating said striker and primer, but being slidably mounted in said housing to allow contact thereof during the flight of the projectile, an escapement device driven from and braking the movement of said bolt, said escapement being eccentrically positioned with regard to the fuse axis, and comprising 65 an anchor and toothed escapement, said anchor being out of equilibrium, and means for preventing movement of said bolt until the departure of the projectile.

4. A percussion fuse for projectiles comprising in combination a striker, a primer, a housing in which said striker and primer are mounted so as to be movable relatively one to the other, a guide in said housing for said striker, a first spring being interposed 80 between said striker and guide, a second spring between the housing and the guide, a radial bolt-member normally separating said striker and primer but being slidably mounted in said housing to allow contact 85 thereof during the flight of the projectile, an escapement device driven from and braking the movement of said bolt, said escapement being eccentrically positioned with regard to the fuse axis, and comprising 90 an anchor and toothed escapement, said anchor being out of equilibrium, and means for preventing movement of said bolt until the departure of the projectile.

5. A percussion fuse for projectiles comprising in combination a striker, a primer, a housing in which said striker and primer are mounted so as to be movable relatively one to the other, a radial bolt-member normally separating said striker and primer but being 100 slidably mounted in said housing to allow contact thereof during the flight of the projectile, said bolt having a forked and bevelled end in which the striker engages, an escapement device driven from and braking the 110 movement of said bolt, said escapement being eccentrically positioned with regard to the fuse axis, and means for preventing movement of said bolt until the departure of the projectile.

6. A percussion fuse for projectiles comprising in combination a striker, a primer, a housing in which said striker and primer are mounted so as to be movable relatively one to the other, a radial bolt-member normally 120 separating said striker and primer but being slidably mounted in said housing to allow contact thereof during the flight of the projectile, said bolt having a forked and bevelled end in which the striker engages, an escapement device driven from and braking the movement of said bolt, said escapement being eccentrically positioned with regard to the

fuse axis, and comprising an anchor and toothed escapement, said anchor being out of equilibrium, and means for preventing movement of said bolt until the departure of the 5 projectile.

7. A percussion fuse for projectiles comprising in combination a striker, a primer, a housing in which said striker and primer are mounted so as to be movable relatively one to 10 the other, a guide in said housing for said striker, a first spring between the striker and guide, a second spring between the housing and the guide, a radial bolt-member normally separating said striker and primer but 15 being slidably mounted in said housing to allow contact thereof during the flight of the projectile, said bolt having a forked and bevelled portion in which said striker engages, an escapement device driven from and braking 20 the movement of said bolt, said escapement being eccentrically positioned with regard to the fuse axis and comprising an anchor and toothed escapement, said anchor being out of equilibrium, and means for 25 preventing movement of said bolt until the departure of the projectile.

8. A percussion fuse for projectiles comprising in combination a striker, a primer, a housing in which said striker and primer are mounted so as to be movable relatively one 30 to the other, a guide in said housing for said striker, a first spring being interposed between said striker and guide, a second spring between the housing and the guide, a radial bolt-member normally separating said striker and primer but being slidably mounted in 35 said housing to allow contact thereof during the flight of the projectile, said bolt having a forked and bevelled portion, in which said striker engages, an escapement device driven from and braking 40 the movement of said bolt, said escapement being eccentrically positioned with regard to the fuse axis, and

means for preventing movement of said bolt until the departure of the projectile. 45

9. A percussion fuse for projectiles comprising a relatively movable striker and primer, a radial bolt-member normally separating said members but being slidably mounted so as to allow contact thereof after 50 firing, a train of wheels driven on movement of said bolt to operate an escapement disposed eccentrically of the fuse axis, means for preventing movement of said bolt prior to 55 firing and a housing in the fuse body for said wheel train and escapement device.

10. A percussion fuse for projectiles comprising a relatively movable striker and primer, a radial bolt-member normally separating said members but being slidably 60 mounted so as to allow contact thereof after firing, a train of wheels driven on movement of said bolt to operate an escapement disposed eccentrically of the fuse axis, said escapement comprising an anchor and a toothed 65 wheel driven by said train of wheels, said anchor being out of equilibrium, means for preventing movement of said bolt prior to firing, and a housing in the fuse body for 70 said wheel train and escapement device.

11. A percussion fuse for projectiles comprising a relatively movable striker and primer, a radial bolt-member normally separating said members but being slidably mounted so as to allow contact thereof after 75 firing, said bolt having a forked and bevelled portion in which said striker engages, a train of wheels driven on movement of said bolt to operate an escapement disposed eccentrically of the fuse axis, means for preventing movement of said bolt prior to 80 firing, and a housing in the fuse body for said wheel train and escapement device.

In testimony whereof I have signed my name to this specification.

ANDRÉ VARAUD.
